DRAIN PIPE CLEANING DEVICE

Herbert N. Wayne, Santa Monica, Calif.

Application December 8, 1933, Serial No. 701,468

3 Claims. (Cl. 4—256)

This invention relates to a device for cleaning drain pipes and more particularly pertains to a device which is especially adapted for use in removing obstructions from the drain pipes of 5 kitchen sinks, laundry trays, lavatories and the like.

An object of the invention is to provide a device of the above character which is adapted to be employed either in directing water under pressure 10 through a drain pipe from the usual faucet or be employed as a combined pressure and suction drain pipe flusher apart from the faucet.

A further object is to provide a drain pipe flushing device which is especially applicable for use 15 in flushing the drain pipes of lavatories, which drain pipes are provided with a side opening adjacent their inlet ends communicating with an overflow opening in the lavatory bowl; the invention 20 contemplating forming the flushing device so that it will afford a seal for the side opening in the drain pipe to prevent the back flow of flushing water into the bowl through the overflow opening in the latter.

With the foregoing objects in view together with 25 such other objects and advantages as may subsequently appear the invention resides in the parts and in the combination, construction and arrangement of parts hereinafter described and claimed, and illustrated by way of example in the 30 accompanying drawing in which:

Fig. 1 is a view of the flushing device as seen in elevation partly in vertical section with portions broken away, and depicting one embodiment of the invention;

Fig. 2 is a detail in section and elevation showing another form of the invention;

Fig. 3 is a view in section illustrating the application of the device as shown in Fig. 2;

Fig. 4 is a view in elevation illustrating the 40 manner of applying the device shown in Fig. 1, when delivering water under pressure to the drain pipe of a lavatory bowl.

Referring to the drawing more specifically, 6 indicates a flexible tube having a sleeve 7 formed 45 at one end thereof for connection with a faucet 8, as shown in Fig. 4. The sleeve is formed with a series of spaced internal resilient ribs 9 extending around its inner periphery for effecting frictional engagement with the faucet. The other 50 end of the tube 6 is formed with an enlargement 10 provided with an annular groove 11 in which is engaged the inner margin of a flexible annular wall 12 having an outwardly flared wall 14 formed in continuation with its outer portion, and which walls 12 and 14 constitute collectively a flexible

cup A or bowl shaped wall, which serves the double purpose of a shield and suction cup as will be later described.

The tube 6 with its associated parts and the walls 11 and 12 are formed of rubber or rubber 5 composition. In order to render the portion of the tube contiguous the cup A substantially stiff, it may be reinforced as by embedding a metallic tube 15 therein.

The portion of the enlargement 10 protruding 10 beyond the groove 11 may be of general hemispherical contour, as indicated at 16 in Figs. 1 and 4, to adapt it for seating on the margin of the intake of a drain pipe 17 of a sink, or the like.

However, in some instances, the protruding end 15 portion of the enlargement 10 may be formed with a cylindrical body portion 18 of an external diameter less than the internal diameter of the outlet 17 and on which cylindrical portion may be formed a plurality of spaced annular resilient 20 flanges 19 having a diameter exceeding that of the pipe 17.

The protrusion, consisting of the cylinder 18 and the flanges 19, is adapted to be inserted into 25 the intake end of the drain pipe with the flanges 19 turned upwardly by reason of their being flexed when inserted in the drain pipe. As a means for sealing off the overflow opening 20 in the drain pipes of lavatories and the like the lower end of the protrusion is formed with a 30 flexible cup-shaped wall 21 which extends downwardly and has its outer margin of a diameter slightly less than that of the internal diameter of the pipe 17 and accordingly is of lesser diameter than the flanges 19, so that the cup 21 may 35 be readily introduced into the intake of the drain pipe and be caused to seat on the spider 22 with which the intake of the drain pipe is equipped.

In the application and operation of the invention, when it is desired to flush the drain pipe 17 40 and to deliver water under pressure thereto, the sleeve 7 is applied to the faucet 8 and the protruding end portion 16, or cylindrical body portion 18, is applied to the inlet of the drain pipe 17. In effecting connection with the drain pipe the cup 45 A may be disposed in a reverse position as shown in Fig. 4, which is accomplished by turning the cup portion inside out, in which instance the inverted cup A will serve as a shield or deflector for such upwardly projected streams or jets of 50 water as may escape from around the portion of the device seating on the margin of the drain pipe inlet.

In some instances however the protruding end portion of the device may be applied to the drain 55

pipe without reversing the cup A in which event the margin of the latter will seat on the bottom wall of the sink or bowl around the drain pipe opening while the side walls 14 thereof together with its upper wall portion 12 will be flexed upwardly.

In either mode of application of the device to the drain pipe opening it will be retained in its seated position by the operator grasping the portion of the tube 6 adjacent the enlargement 10 and exerting sufficient downward pressure thereon to maintain the device in engagement with the margin of the opening of the drain pipe in opposition to back pressure of liquid in the latter.

Where the device is constructed as shown in Fig. 2 it is applied in the manner above set forth but in this instance the resilient flanges 19 will, on being positioned within the drain pipe 17, be compressed and upturned at their margins as shown in Fig. 3 thereby effecting a tight sealing action since back pressure of liquid on the lower end of the protrusion will tend to force the margins of the flanges tightly against the inner periphery of the drain pipe 17.

The protrusion is of such length that when inserted in the drain pipe intake as shown in Fig. 3 the margin of the cup 21 will seat in the spider 22 and be caused to spread outwardly under downward pressure imposed on the tube 6 by the operator, and thereby cause the outer margin of the cup 21 to press against the inner periphery of the drain pipe and effectively close the communication between the overflow opening 20 and the portion of the drain pipe beneath the spider 22 so that on directing water under pressure through the tube 6 into the drain pipe such water will be prevented from flowing back through the opening 20.

After having thus applied the device water under pressure is delivered to the drain pipe on opening the valve of the faucet 8.

By providing the sleeve 7 with its internal flexible or resilient ribs 9 a tight frictional en-

gagement will be effected between the sleeve and the faucet.

When it is desired to apply the device as a combined suction and pressure slusher the cup A is applied over the inlet of the drain pipe while in its normal position as shown in Fig. 1 and the tube 6 is folded upon itself to close the passage therethrough, whereupon the cup A may be depressed and retracted by reciprocating the tube so as to effect alternate pressure and suction action on liquid contained in the drain pipe 17, in the manner common to the use of ordinary drain pipe flushers.

I claim:

1. In a drain pipe flushing device, a tube, means for attaching one end of said tube to a faucet, a protuberance on the other end of said tube adapted to be inserted in the intake end of a drain pipe, and a resilient cup-shaped wall on the lower end of said protuberance of a diameter less than that of the drain pipe adapted to be spread to effect a sealing of the interior of the drain pipe.

2. In a drain pipe flushing device, a tube, means for attaching one end of said tube to a faucet, a protuberance on the other end of said tube adapted to be inserted in the intake end of a drain pipe, a resilient cup-shaped wall on the lower end of said protuberance of a diameter less than that of the drain pipe adapted to be spread to effect a sealing of the interior of the drain pipe, and a resilient annular flange carried by said protuberance above said cup having a diameter exceeding that of the drain pipe.

3. In a drain pipe flushing device, a tube, means for attaching one end of said tube to a faucet, a protuberance on the other end of said tube adapted to be inserted into the intake end of a drain pipe, means on said protuberance for effecting sealing of the drain pipe and a flexible cup shape wall projecting from said protuberance above said sealing means.

HERBERT N. WAYNE.
